UNITED STATES PATENT OFFICE.

JOHAN M. K. PENNINK, OF AMSTERDAM, NETHERLANDS.

SAND FILTER.

No. 895,296.

Specification of Letters Patent.

Patented Aug. 4, 1908.

Application filed October 3, 1907. Serial No. 395,755.

To all whom it may concern:

Be it known that I, JOHAN M. K. PENNINK, director of the municipal waterworks of Amsterdam, a subject of the Queen of the 5 Netherlands, residing at 629 Keizersgracht, Amsterdam, in the Kingdom of the Netherlands, have invented certain new and useful Improvements in or Relating to Sand Filters, of which the following is a specification.

It is well known that the biological and more particularly, the bacteriological action of a sand filter is only satisfactory when the upper layer of the sand becomes covered with 15 fine vegetable fibers, the residues of water animalculæ, and the suspended solid matters of the unfiltered water, as in this condition such top covering or layer effectually holds back even the smallest particles in the water. Indeed it is only when so covered that the filter 20 furnishes pure water and for this reason it is necessary to await the formation of a new covering before again putting the filter in use, each time the filter is cleaned, when, of course 25 the old covering is destroyed. This involves much loss of time and water each time the filter is cleaned and such cleaning is always necessary when the covering of plankton or algae becomes less permeable at some parts 30 than is desirable for the filter then no longer delivers a sufficient volume of water, or on increasing the pressure of the water in order to force the desired quantity through it, the water delivered decreases in purity as 35 at the higher pressure fine particles are easily carried along. In order to clean such a filter it is first drained dry, the covering of algae and the uppermost layers of sand lying immediately below it are then removed by 40 paring off with shovels. At the same time destruction of the next lower layer of sand is unavoidable, as in cleaning the filter such layer is trodden over and barrows or the like are wheeled over it. Furrows, footprints, 45 and the like are therefore formed in the upper surface of such lower layer and finally the whole of the upper surface or top of the sand has to be raked and turned over before the filter can be again started.

50 Removing the covering of algae by spraying is not desirable for by such a process the upper surface of the sand would be still more disturbed than it is by paring it off.

Now according to this invention the efficiency of the filter is increased by facilitating the cleaning operation, the invention having

reference to an improved method of cleaning such filters and to means for this purpose, whereby the necessary cleaning can be effected in a short time by flushing with water without the flushing water destroying or even touching the active filtering layer of sand. For this purpose, according to this invention the uppermost layer of sand in the filter is covered with a preferably smooth 60 cloth that lies closely thereon and which is made of a textile material adapted to resist rotting as long as possible, such for example as ramie. To assist its resistance to rotting the material of which the cloth is formed is 65 preferably impregnated with a suitable medium. The cloth is attached in a suitable manner to the side walls of the filter and is arranged to incline towards the middle or towards other points. At the lowest point 70 or points the cloth is formed with an orifice or orifices communicating with a pipe built into the filter bed and into which the end or ends of the cloth at such part around the orifice or orifices freely hang down. This pipe is 75 led out of the filter and is furnished with a device for controlling the flow of water therethrough.

The use of cloths in filters has already been tried, in such cases however the cloth formed 80 a preliminary filter, and was arranged separately from the sand layer so that it acted in a similar manner to a sand filter. For this purpose it was kept rough to facilitate a covering of algae forming in and upon it. When 85 this covering became too thick, the cloth had to be washed out whereby the covering of algae was entirely destroyed. The cloth so arranged therefore suffers from the same disadvantage as a sand filter and after each 90 cleaning will only work properly when a new filtering skin has formed upon the cleaned cloth.

The arrangement of the cloth according to this invention differs from that heretofore 100 proposed in that it lies closely upon the sand layer. The covering of algae forms very quickly, first in the upper sand layer, and then on the underside of the cloth between the fibers thereof, and finally upon the cloth 105 itself; in this way the covering of algae lying upon the layer of sand, which would otherwise be liable to destruction by water animalculæ in places, and to become cracked, is efficiently protected by the cloth lying over 110 it. The covering of algae formed under, in and upon the cloth will therefore be much

more durable and consequently the bacteriological action of the filter will be increased.

A further advantage of the cloth covering is that the covering of algae, when it has become insufficiently permeable, can be removed as far as necessary by simply flushing the cloth with water without touching the upper layers of sand.

Figure 1 of the accompanying drawing 10 shows in vertical longitudinal section a constructional example of filtering plant embodying this invention. Fig. 2 is a plan of the filter bed. Fig. 3 illustrates an arrangement of the cloth covers for larger filter 15 basins.

Upon the filter bed 2, which consists of pebbles, sand etc. and which is placed in the filter basin 1 in the usual way, is laid a cloth cover 3 formed of an impregnated textile material such for example as ramie. The outer edges of the cloth 3 are detachably connected on all sides to the side walls of the basin 1 for which purpose the cloth edges are preferably laid upon a ledge 4 and held 25 thereon by stones 5 or the like.

In its center the cloth cover has a tubular outlet 6, by which it is suspended in the upper end of a vertical pipe 7 that runs downwardly through the filter basin, and under it 30 to a part where it is provided with a shut off valve or other device 8. The draw off pipes 9 for the filtered pure water are arranged in the usual way on the floor of the filter basin and communicate at one side or on both sides with a common pipe 10, 35 see Fig. 2.

Should the filter bed be too large for a single cloth it is advisable to use several such cloths, as indicated at 11 in Fig. 3, the several cloths being connected together with good joints and each being provided with a central draw off pipe 12.

The working of the filter is as follows: After the formation of the filter bed 2 from 45 the various layers of pebbles and sand placed in the filter basin 1, the cloth cover 3 is laid upon the upper layer and secured to the ledges 4; the central tubular branch 6 is caused to hang down in the mouth of the 50 vertical pipe 7 and the joint therewith is made properly tight. When the cock 8 is closed the unfiltered water is delivered to the filter, filtration and formation of the covering of algae then takes place in a very 55 short time under, in and above, the cloth covering 3.

Should the covering of algae become so insufficiently permeable that the removal thereof is necessary the unfiltered water 60 supply is shut off and the cock 8 is opened.

All the unfiltered water in the filter basin will then suddenly run out and carry away with it the entire covering of algae lying on the top of the cloth 3 without even touching the 65 or disturbing the layer of sand lying imme-

diately underneath the cloth. Any algae residues still remaining can be detached from the cloth by spraying with water and consequently also removed. Should it be necessary to also remove the algae adhering to the underside of the cloth, pure water can be forced in through the pipes 9. A gentle stream of water will thereby be caused to flow along the underside of the cloth 3 so as to carry the superfluous algae with it down into the draw off pipe 7 without disturbing the upper layers of sand.

For the purpose of cleaning the cloth cover it may be completely taken off and washed elsewhere but in all these operations the upper layer of sand is not disturbed. Where as formerly the operation of cleaning took several days it can, as before described, be now accomplished in as many hours and with much less expenditure of labor. In winter, 85 when the filters are frozen over, the filtering skin can be washed away without having to first remove the covering of ice. After being cleaned the filter is at once ready for use again.

Existing sand filtering plants can be readily adapted for cleaning according to this invention without material alteration.

What I claim is:

1. In a sand filter, a filter basin, a filter bed 95 therein, a filter cloth lying closely on the top layer of sand forming said filter bed and formed with an opening, a conduit with which the opening of said cloth communicates and means for controlling at will the 100 passage through said conduit.

2. In a sand filter, a filter basin, a filter bed 105 therein, a filter cloth lying closely on the top layer of sand forming said filter bed and formed with an opening, means for securing the outer edges of said cloth to the sides of said filter basin, a conduit with which the opening of said cloth communicates and means for controlling at will the passage through said conduit.

3. In a sand filter, a filter basin, a filter bed 115 therein, a filter cloth lying closely on the top layer of sand forming said filter bed and formed with an opening, a ledge on the side walls of said basin above said filter bed, means for securing the outer edges of said cloth on said ledge, a conduit with which the opening of said cloth communicates and means for controlling at will the passage through said conduit.

4. In a sand filter, a filter basin, a filter bed 125 therein, a filter cloth lying closely on the top layer of sand forming said filter bed and formed with a centrally arranged opening, a conduit with which the opening of said cloth communicates and means for controlling at will the passage through said conduit.

5. In a sand filter, a filter basin, a filter bed 130 therein, a filter cloth lying closely on the top layer of sand forming said filter bed and

- formed with an opening, a conduit, with which the opening in said cloth communicates, extending vertically through said filter bed and through the bottom of said filter 5 basin, and means for controlling at will the passage through said conduit.
6. In a sand filter, a filter basin, a filter bed therein, a filter cloth lying closely on the top layer of sand forming said filter bed and 10 formed with an opening, a conduit with which the opening of said cloth communicates, and a valve for controlling at will the passage through said conduit.
7. In a sand filter, a filter basin, a filter bed 15 therein, a filter cloth lying closely on the top layer of sand forming said filter bed and formed with an opening, a vertical conduit into the mouth of which extend the edges of the said cloth around the opening thereof, 20 and means for controlling at will the passage through said conduit.
8. In a sand filter, a filter basin, a filter bed therein, a filter cloth lying closely on the top layer of sand forming said filter bed and 25 formed with an opening, a conduit with which the opening of said cloth communicates, means for spraying water on the upper surface of said cloth, and means for controlling at will the passage through said conduit.
- 30 9. In a sand filter, a filter basin, a filter bed therein, a filter cloth lying closely on the top layer of sand forming said filter bed and formed with an opening, a conduit with which the opening of said cloth communicates, means for controlling at will the 35 passage through said conduit, and means for forcing pure water into said filter bed below said cloth.
10. In a sand filter, a filter basin, a filter 40 bed therein, a filter cloth lying closely on the top layer of sand forming said filter bed and
- formed with an opening, a conduit with which the opening of said cloth communicates, means for controlling at will the passage through said conduit and pipes arranged in said filter bed at approximately three-fourths of the height thereof adapted to deliver pure water into said filter bed below said cloth. 45
11. In a sand filter, a filter basin, a filter bed therein, a filter cloth lying closely on the top layer of sand forming said filter bed and depending towards a part lower than the remainder in which part an opening is formed, a conduit with which the opening of said cloth communicates and means for controlling at will the passage through said conduit. 50
12. In a sand filter, a filter basin, a filter bed therein, a number of filter cloths lying closely on the top layer of sand forming said filter bed and each formed with an opening, conduits with which the openings of said filter cloths communicate, and means for controlling at will the passage through said conduits. 55
13. In a sand filter, a filter basin, a filter bed therein, a filter cloth lying closely on the top layer of sand forming said filter bed and depending towards a part lower than the remainder in which part an opening is formed, 60 means for securing the outer edges of said cloth to the sides of said filter basin, a conduit with which the opening of said cloth communicates and means for controlling at will the passage through said conduit. 65
- In testimony whereof I have hereunto set my hand in presence of two subscribing witnesses.

JOHAN M. K. PENNINK.
